UNITED STATES PATENT OFFICE.

EDWARD WAIGAND, OF NAMPA, IDAHO.

WRAPPING-PAPER SUPPORT.

1,300,061.

Specification of Letters Patent.

Patented Apr. 8, 1919.

Application filed July 9, 1917. Serial No. 179,516.

To all whom it may concern:

Be it known that I, EDWARD WAIGAND, a citizen of the United States, residing at Nampa, in the county of Canyon and State of Idaho, have invented certain new and useful Improvements in Wrapping-Paper Supports; and I do declare the following to be a full, clear, and exact description of the invention, such as will enable others skilled in the art to which it appertains to make and use the same.

My invention relates to that class of devices intended to support rolls of wrapping paper in stores and numerous other kinds of business establishments.

The principal object of my invention is to provide a horizontal bar to rest on the roll of paper to exert a braking action thereon to control the rotation of the roll, the ends of said bar having guides which are mounted for vertical sliding on a pair of posts which rise from the upper sections of the bearings, whereby when said sections are swung free of the lower sections, said brake bar is similarly disposed to inactive position so that it will interfere in no manner with removing the shaft and applying a new roll of paper.

A still further object is to provide a novel cutting means for the paper as it is unwound from the roll.

With the foregoing general objects in view the invention resides in the novel features of construction and unique combinations of parts to be hereinafter fully described and claimed, the descriptive matter being supplemented by the accompanying drawings which form a part of this specification and in which:

Figure 1 is a front elevation of the improved wrapping paper support;

Fig. 2 is a top plan view thereof;

Fig. 3 is an end elevation; and

Fig. 4 is an enlarged top plan of a portion of the cutting means, showing more particularly the manner in which the two pivoted bridge members swing forwardly when the paper is grasped and pulled from the roll.

In the drawings above briefly described, the numerals 1 designate a pair of spaced end frames which are connected by a plurality of bars 2, said frames being also equipped with outstanding feet 3 whereby they may be secured to a counter or any other suitable support. The upper ends of

the frames 1 are provided with two-part bearings 4, each bearing being formed of a lower fixed section 5 and an upper vertically swinging section 6 hinged thereto at 7, a spring catch or the like 8 being provided for holding the two sections in operative relation. The bearings 4 support the opposite ends of a shaft 9 which extends between the end frames 1 and is adapted to pass through the center of a roll of paper such as that indicated at R in Fig. 3, and due to the construction of said bearings, they may be easily opened and closed to permit the shaft to be inserted and removed when occasion may demand, it being simply necessary to release the spring catches 8 or the equivalent devices which may be provided.

For the purpose of controlling the rotation of the reel or roll of the paper a horizontal bar 10 is provided, said bar being adapted to rest on the roll to exert a braking action thereon. The ends of the bar 10 are provided with suitable guides 11 which are slidable vertically on a pair of posts 12 which rise from the upper sections 6 of the bearings 4 and are provided on their upper ends with suitable stops 13 which prevent dislocation of the bar 10. It is to be observed that although the bar 10 will rest on the roll of paper when the latter is applied in the holder, said bar will be disposed to inoperative position automatically, when the bearings 4 are opened to permit the shaft 9 to be removed before applying a new roll of paper. This is caused by the fact that upward swinging of the bearing sections 6 causes the posts 12 to incline downwardly from the bearings, whereupon the bar 10 will slide to what are normally the upper ends of said post, being limited in its movement, however, by the stops 13.

A suitable shelf 14 is secured at its ends to the end frames 1, at the front edges of the latter, said shelf preferably inclining downwardly to a slight extent from the frame as will be clear from Fig. 3. The paper from the roll R is adapted to be passed over the shelf 14 and under a cutter plate 16 which overlies said shelf, the rear edge of said plate being preferably rolled forwardly to provide a comparatively large bead 17. This bead serves not only to reinforce the cutter plate 16, but also guides the paper between the shaft 14 and said plate. Spring hinges 18 are secured to

the bead 17 and to the end frames 1, said hinges exerting their tension to force the plate 16 downwardly onto the paper so that when the latter is drawn forwardly and 5 then pulled in the usual manner across the edge of said plate 16, effective cutting of the paper will take place.

As shown most clearly in Figs. 2 and 4, the shelf 14 is provided with a central 10 notch 19, opening through the front edge of said shelf, whereas the cutter plate 16 is provided with a similar but smaller notch 20 above said notch 19, these notches being provided in order that a portion of the 15 paper will be exposed to be grasped by the thumb and fingers. A pair of pivoted bridge members 21 are provided to bridge the interrupted portion of the cutting edge and the plate 16, said members being mounted 20 to swing outwardly as the paper is grasped and pulled forwardly, but being returned to their initial positions, by means of suitable springs 22, said springs turning the members 21 around their pivots to 25 the extent permitted by the stops 23. When these stops are encountered the straight edges 24 of the bridge members 21 are in alinement, so that they form a continuation 30 of the cutting edge of the plate 16, thus insuring that the paper shall be torn upon a straight uninterrupted line.

I attach great importance to the fact that the posts 12 swing rearwardly when the 35 bearings 4 are opened, this movement serving to dispose the brake bar 10 to such a position as to prevent the same from interfering in any manner with the application of a new roll of paper. It is worthy of note that when the bearings are opened, a new 40 roll of paper may be easily put in place without the necessity of holding springs and the like out of the way as is the case with a number of paper supports now on the market. Furthermore, it is to be observed 45 that the brake bar will place the same tension or braking action upon the roll of paper, whether said roll be large or small.

Copies of this patent may be obtained for five cents each, by addressing the "Commissioner of Patents, Washington, D. C."

The cutting mechanism described, and the bead 17 on the rear edge of the cutter plate 16, are also deemed highly important features of the invention. Since probably the best results are obtained from the specific constructions shown and described, such construction constitutes the preferred form of the improved paper support. It is to be 50 understood, however, that within the scope of the invention as claimed, numerous minor changes may be made without sacrificing the principal advantages.

I claim:

A wrapping paper support comprising a pair of end frames having means for supporting a roll of paper, a transverse shelf secured at its ends to said frames and positioned at the front edges of the latter, said shelf being adapted to receive thereon the paper unwound from said roll and having in its front edge a central notch, a sheet metal cutter plate overlying said shelf and having its rear edge rolled upwardly and 70 forwardly to form a bead which serves to guide the paper between the cutter plate and shelf and also as reinforcing means for said plate, spring hinges secured to the upper side of said bead and to said end frames 75 for forcing said cutter plate downwardly onto the paper to place tension on the latter and for permitting upward swinging of said cutter plate entirely away from said shelf when inserting the paper between the 80 two, the front edge of said cutter plate having a notch positioned above the notch of said shelf, and a pair of spring restored bridge members pivoted to said cutter plate and having straight front edges in alinement and extending across the notch of said plate.

In testimony whereof I have hereunto set my hand in the presence of two subscribing witnesses.

EDWARD WAIGAND.
